Application June 24, 1940, Serial No. 342,158

3 Claims. (Cl. 41—18)

This invention relates to signs and more particularly to metallic signs.

The object of the invention is to provide an improved metallic sign characterized by lightness, ease and cheapness of manufacture, durability, and of a finish suggestive of massiveness found ordinarily only in the most expensive types of solid cast metal signs.

The invention consists in the novel construction, arrangement and combinations of parts and the method of producing such arrangements, as hereinafter more particularly described and claimed.

One sheet of drawings accompanies this specification as part thereof, in which like reference characters indicate like parts throughout.

Figure 1 is a plan view of the core or base of the improved sign at an intermediary stage of manufacture.

Figure 2 is a plan view of a complete sign exemplifying the present invention.

Figure 3 is a vertical cross section taken on line 3—3 of Figure 2 and indicating diagrammatically one step in the manufacture.

Among the most attractive types of signs now in use are those cast from solid metal, brass, bronze, aluminum or the like with the lettering in high relief. Such signs enjoy favor for interior use on desks in offices, as markers, and as indicators in parks, cemeteries and the like but are so expensive by reason both of the material required and the processes involved in their manufacture, that they are rarely, if ever, used for ordinary advertising purposes.

Aside from the high cost of such cast metal signs, their weight constitutes an almost fatal objection in connection with ordinary advertising purposes.

The sign of the present invention creates the effect of the most substantial and expensive type of solid cast metal signs but uses only a fractional part of the metal, is very light and readily adapted for quite general use for advertising purposes.

In the advertising field, it is highly desirable to combine with signs of standardized manufacture and uniformity of display certain individual, distinctive features particularly appropriate to the immediate place of display. Thus, for instance, advertising signs for popular trade-mark brand goods will always show the trade-mark and probably other features in the identical form, accompanied, however, by the name of the particular store over which the sign is displayed. Such signs would, if cast from solid metal, re-

quire an individual treatment and the cost would be totally prohibitive.

In accordance with the present invention, the sign includes a base or core 1, which may be formed of wood, fiber-board, papier-mâché, plaster or other non-metallic material. These cores may be embossed with characters 2 in large numbers, such characters 2 representing the standardized, uniform display to be shown on all of the signs. Individual characters 3 will then be selectively positioned on the core to make the particular name or representation distinctive of the particular place of display, the characters 3 being formed of similar material to that used in the core 1 and secured to core 1 in any desirable manner at that stage of assembly.

Over the core containing the embossed characters 2 and the selectively assembled characters 3 will then be deposited by any suitable process 20 metal to provide a continuous, seamless, homogeneous layer of metal. Among the processes which may be utilized for depositing this metal layer is one by which molten metal is sprayed, as by a sprayer 5, indicated diagrammatically in Fig. 3, and in which the molten particles of metal coalesce and form a homogeneous layer of metal on the surface against which the spray is directed. Electrolysis also provides another means 25 by which such a layer may be deposited on the core.

In accordance with the present invention this homogeneous metal layer completely surrounds the core, as illustrated at 4 in Fig. 3, and thus provides a seamless container entirely enclosing the core with its assembled characters with a metal wall of sufficient thickness to provide rigidity to the core and permit the grinding or buffing of the high relief characters, and thus results 30 in a sign closely simulating in effect a solid cast metal sign but having the characteristics of satisfactory rigidity, great lightness, relative cheapness both in the amount and cost of materials used and ease of manufacture. Signs embodying the present invention closely simulate in appearance 35 genuine solid cast metal signs.

Having thus fully described my invention, I claim:

1. A sign comprising a relatively light non-metallic fibrous core having characters formed thereon in relief, and a homogeneous seamless casing of metal formed thereon and completely enclosing said core and characters of sufficient thickness to give rigidity and permit polishing to give the effect of a cast metal sign.

2. The method of making a sign comprising

forming a base of non-metallic material with characters in relief integral therewith, securing other selected characters to the base in relief, encasing the entire base with assembled characters with a homogeneous seamless metallic layer of sufficient thickness to hold said base and assembled characters and permit polishing relief character faces to give the effect of a cast metal sign.

3. The method of making a sign comprising 10

5 forming a base with characters in relief integral therewith, securing other selected characters to the base in relief, encasing the entire base with assembled characters with a homogeneous seamless metallic layer of sufficient thickness to hold said base and assembled characters and permit polishing relief character faces to give the effect of a cast metal sign.
